UNITED STATES PATENT OFFICE

100,088

DESIGN FOR A FLUSH PLATE

Harry J. Carlson, Grove City, Pa.

Application March 24, 1936, Serial No. 61,758

Term of patent 14 years

To all whom it may concern:

Be it known that I, Harry J. Carlson, a citizen of the United States, residing at Grove City, in the county of Mercer and State of Pennsylvania, have invented a new, original, and ornamental Design for Flush Plates, of which the following is a specification, reference being had to the accompanying drawing, forming part thereof.

Figure 1 is a front view in elevation of a flush plate showing my new design, the surface orna-

mentation shown in opposite corners of the plate to be continued throughout the entire exposed surface of the flush plate,

Figure 2 is a side view in elevation, and

Figure 3 is a top edge view.

I claim:

The ornamental design for a flush plate, as shown and described.

HARRY J. CARLSON.
